United States Patent Office.

JOHN WILCOX, OF THOMPSONVILLE, CONNECTICUT.

Letters Patent No. 63,127, dated March 19, 1867.

IMPROVEMENT IN FAUCETS.

The Schedule referred to in these Letters Patent and making part of the same.

TO ALL WHOM IT MAY CONCERN:

Be it known that I, JOHN WILCOX, of Thompsonville, in the county of Hartford, and State of Connecticut, have invented a new and improved Faucet; and I do hereby declare that the following is a full, clear, and exact description thereof, which will enable others skilled in the art to make and use the same, reference being had to the accompanying drawings, forming a part of this specification.

My invention consists in constructing a faucet in such a manner that the liability to leak from any part is greatly lessened; the faucet valve being doubly packed, and the packing of all the joints, as well as that of the valve, being secured in recesses provided for the purpose, as will be hereafter described.

The drawing represents a central vertical section of the faucet.

A is the shell, which is attached to the barrel or other vessel in the usual manner. B is the valve joint; C is the stem; D is a socket screwed into the lower portion of the shell; E represents the cap, and F the part attached to the stem by which the faucet is operated. The faucet is operated by turning the stem, the lower portion of which has a screw-thread upon it, which works in a female screw in the socket D, as seen in the drawings. To form a double packed joint for the valve at B there is a thimble, *a*, screwed into the shell and forming a recess for packing. There is another recess formed in the valve portion of the stem, as seen at *b*. A single recess is also seen in the socket-piece D, which contains packing, and forms a joint with the lower portion of the shell, as seen at *d*. The same arrangement is seen at the top of the shell, the recess for the packing being in the cap E. *e* is a metallic plate resting upon a shoulder in the shell and supporting a piece of elastic packing under the cap, and marked *f*. *g* represents an aperture through the valve stem for "waste" when the faucet is used in certain situations. It will be noticed as a distinguishing feature of this faucet that the packing of the valve and all the joints is secured in recesses. The packing is in the form of rings of rubber, or some other elastic material, and laid into the recesses and pressed by metallic surfaces, as seen in the drawing, by the screws. This packing is marked *o* and the recesses are marked *p*.

Having thus described my invention, what I claim as new, and desire to secure by Letters Patent, is—

The faucet, consisting of the shell A, stem C, socket D, thimble *a*, valve joint B, and packing recesses *p*, constructed as herein set forth for the purpose specified.

The above specification of my invention signed by me this 21st day of November, 1866.

JOHN WILCOX.
